US0D1058810S

(12) **United States Design Patent** (10) Patent No.: **US D1,058,810 S**
(45) Date of Patent: ** Jan. 21, 2025

(54) **HUMERAL IMPLANT**(71) Applicant: **HOWMEDICA OSTEONICS CORP.**, Mahwah, NJ (US)(72) Inventors: **Kevin P. Knox**, Fort Wayne, IN (US); **Austin Wyatt Mutchler**, Warsaw, IN (US); **Shawn M. Gargac**, Fort Wayne, IN (US)(73) Assignee: **HOWMEDICA OSTEONICS CORP.**, Mahwah, NJ (US)(**) Term: **15 Years**(21) Appl. No.: **29/872,827**(22) Filed: **Mar. 20, 2023****Related U.S. Application Data**

(62) Division of application No. 29/792,369, filed on Mar. 25, 2022, now Pat. No. Des. 985,125, which is a division of application No. 29/707,805, filed on Oct. 1, 2019, now Pat. No. Des. 951,449.

Primary Examiner — Leanne Was-Englehart*Assistant Examiner* — Justin A Johnson(74) *Attorney, Agent, or Firm* — DUANE MORRIS LLP**CLAIM**

The ornamental design for a humeral implant, as shown and described.

DESCRIPTION

FIG. 1 is a top side perspective view of a humeral implant of our design;

FIG. 2 is a bottom perspective view thereof;
FIGS. 3-6 are front, back, left, and right side views, respectively, thereof;

FIG. 7 is a top view thereof; and,

FIG. 8 is a bottom view thereof.

All features illustrated in broken lines form no part of the claimed design.

1 Claim, 5 Drawing Sheets# US D1,058,810 S
